US00D924224S

(12) **United States Design Patent** (10) Patent No.: **US D924,224 S**
(45) Date of Patent: ** Jul. 6, 2021

(54) **COMPUTER TERMINAL**

(71) Applicant: **Dataking, Inc**, Anyang-si (KR)

(72) Inventor: **Sun Kyou Park**, Seoul (KR)

(73) Assignee: **Dataking, Inc.**, Anyang-si (KR)

(**) Term: **15 Years**

(21) Appl. No.: **35/509,224**

(22) Filed: **Apr. 8, 2019**

(80) **Hague Agreement Data**

Int. Filing Date: **Apr. 8, 2019**

Int. Reg. No.: **DM/207391**

Int. Reg. Date: **Apr. 8, 2019**

Int. Reg. Pub. Date: **May 1, 2020**

(51) **LOC (13) Cl.** **14-02**

(52) **U.S. Cl.**

USPC **D14/307**

(58) **Field of Classification Search**

USPC D6/300, 310; D14/300–302, 307, 371,
D14/372, 374, 900–902; D19/113;
D20/19, 41; D16/132, 133, 221, 222,
D16/225–227

CPC A47F 9/047
